UNITED STATES PATENT OFFICE.

HERBERT ELIJAH KEELER, OF CHICAGO, ILLINOIS.

ICE PICK.

Application filed September 20, 1922. Serial No. 589,358.

To all whom it may concern:

Be it known that I, HERBERT ELIJAH KEELER, a citizen of the United States, residing at Chicago, in the county of Cook 5 and State of Illinois, have invented a certain new and useful Improvement in Ice Picks, of which the following is a specification.

My invention relates to ice picks, more 10 particularly of the type in which the handle is slidably mounted upon a pointed rod for imparting a blow to it, and a helical spring is interposed between the parts to normally hold the rod in projected position. In previous 15 constructions the parts have been so designed that the inner end of the rod was apt to become fouled by the turns of the spring, thus causing the parts to jam and preventing proper operation. The object of my invention is to provide simple and efficient 20 means for preventing such condition. Another object of the invention is to provide a simple and inexpensive form of assembly so that the parts may be readily produced on ordinary machinery and readily 25 assembled after the individual parts have been produced.

I obtain my objects by the mechanism illustrated in the accompanying drawings 30 in which—

Figures 1 and 2 are assembly views chiefly in diametral section showing the parts in different relative positions.

Figure 3 is a top plan view of Figure 2.

Figure 4 is a distributive view showing the relation of the pointed rod to the supporting sleeve.

Figure 5 is an assembly view chiefly in diametral section showing a modified form 40 of the device.

Figure 6 is an assembly view chiefly in diametral section showing still another modification in which the rod is introduced from the lower end of the handle.

Figure 7 is a bottom plan section on the line 7—7, Figure 6.

Like numerals denote like parts throughout the several views.

Referring first to the type of device 50 shown in Figures 1 to 4 inclusive, a rod 1 is pointed at the outer end for acting upon the ice. At a location somewhat below the upper end of the rod there is a collar 2 which by preference is integral with the rod. 55 This collar forms an abutment for the lower end of a helical compression spring 4 which

encircles the upper end of the rod and is contained within the hollow stem of the handle 6. In this type the lower end of the handle is closed so as to form a stop for the 60 collar 2 although it is apertured to accommodate and guide the rod beneath the collar. By preference the handle has a weighted head 8 which is not only convenient to be 65 grasped by the user but adds weight to the moving parts so as to increase the force of the blow delivered to the upper end of the pointed rod when in action. In order to prevent the tool from rolling when laid on the table or other surface it is desirable that 70 the head have a flattened side 9 as illustrated in Figure 3.

According to the design shown in Figures 1 to 4 the upper end of the handle is closed by screw plug 10 which forms an abutment 75 for the upper end of a tube or sleeve 12 which is spaced far enough from the inner walls of the handle to accommodate the presence of the upper end of the spring and extends down far enough so as to overlap 80 the upper end of rod 1 when the collar 2 is in contact with the lower end of the handle as illustrated in Figure 1. The rod is freely 85 slidable within the tube and the lower end of the tube is preferably bevelled to insure non-interference with the spring.

In operation, the parts normally assume the position shown in Figure 1. In cracking ice the operator places the point of the rod at the location desired and then imparts a series of sharp blows by rapidly moving the handle a number of times down upon the rod so that the upper end thereof is engaged by the plug 10 as illustrated in Figure 2. After 90 each blow is struck the spring 4 tends to return the parts to the original position. The tube 12 confines the spring to its proper location and prevents it from buckling or in any wise interfering with the free movement 95 of the rod. In other words, the tube constitutes means for holding the spring in alignment and for separating the upper end 100 of the rod at all times from the spring.

The type shown in Figure 5 is analogous to the type hereinabove described but in this 105 case the spring 14 does not extend substantially throughout the length of the handle but abuts the lower end of a tube or thimble 15 which occupies the entire cylindrical space between the rod and inner wall of the 110 handle. It will be evident that in this form, as in the previous one, the tubular member

always protects the upper end of the rod 1 and prevents it from coming into engagement with the spring.

In Figures 6 and 7 I have shown still another type which is constructed similarly to the type shown in Figures 1 to 4 except that in lieu of the plug 10 the head 18 of the handle is solid and the lower end of the handle instead of being integral is closed by a screw plug 20 controlled by a nut 21. The plug is of sufficient diameter to permit all of the parts within the handle to be withdrawn through the opening which the plug closes. One advantage in this type is that the rod 15 strikes an integral portion of the handle instead of striking a part which is simply screwed thereinto.

It will be observed that in all of these various types of construction there is a tubular element which at all times prevents the inner end of the rod from coming into contact with the spring, thus avoiding any possibility of the rod becoming caught in the spring. Also the spring itself is always held in alignment and loosely confined to the position it ought to occupy. It is evident that the size and shape of the head on the handle may be greatly varied without departing from the spirit of the invention.

Having thus described my invention, what I claim as new and desire to secure by Letters Patent is:

1. An ice pick having a pointed rod, a handle slidably mounted on the rod, a helical spring surrounding the rod within the handle, and a tubular element within the handle and encircling the rod, said tubular element being adapted to engage the spring and keep the turns thereof out of contact with the inner end of the rod.

2. An ice pick having a pointed rod with

a collar fixed upon it between its ends, a hollow handle slidably mounted upon the rod and enclosing the upper end thereof, the lower end of the handle being apertured to accommodate the rod, and being otherwise closed to form a stop adapted to be engaged by the collar to limit the outward movement of the rod, a helical spring resting at one end upon the upper surface of the collar and at the other end abutting the inner end of the handle, and a tubular element within the handle interposed between the spring and the rod for preventing the upper end of the rod from jamming against the turns of the spring.

3. An ice pick having a hollow handle, a pointed rod slidably mounted within the handle, means for limiting the outward movement of the rod, a helical spring enclosed within the handle, the spring abutting the rod at one end and the handle at the other for urging the rod outward, and a tube forming a lining for the upper portion of the spring, said tube extending downward far enough to cover the upper end of the rod when the latter is projected outward the maximum distance.

4. An ice pick having a hollow handle which is solid at its upper end, a pointed rod slidably mounted within the handle, a collar rigidly mounted on the rod between the ends, a helical spring enclosed within the handle and adapted to urge the rod outward, and a screw plug closing the lower end of the handle, said plug being apertured to guide the rod and being adapted to limit the outward movement of the collar.

In witness whereof, I have hereunto subscribed my name.

HERBERT ELIJAH KEELER.
